(57) CLAIM

We claim the ornamental design for a portable, foldable, rotatable lap desk with slide out extension and stabilizing legs for car floor support, as shown and described.

DESCRIPTION

FIG. 1 is a perspective view of a portable, foldable, rotatable lap desk with slide out extension and stabilizing legs for car floor support showing our new design with the slide out extended;

FIG. 2 is a side elevational view thereof showing the slide out extended;

FIG. 3 is an elevational view of the opposing side thereof showing the slide out extended;

FIG. 4 is an end elevational view thereof;

FIG. 5 is an elevational view of the opposing end thereof;

FIG. 6 is a top plan view thereof showing the slide out extended; and,

FIG. 7 is a bottom plan view showing the slide out extended.
